(57) **CLAIM**

The ornamental design for a movable weighted food barrier as shown and described.

DESCRIPTION

FIG. 1 is a front end elevation view of a movable weighted food barrier.

FIG. 2 is a rear end elevation view of the movable weighted food barrier of FIG. 1.

FIG. 3 is a right side elevation view of the movable weighted food barrier of FIG. 1.

FIG. 4 is a left side elevation view of the movable weighted food barrier of FIG. 1.

FIG. 5 is a top view of the movable weighted food barrier of FIG. 1.

FIG. 6 is a bottom view of the movable weighted food barrier of FIG. 1; and,

FIG. 7 is a perspective view of the movable weighted food barrier of FIG. 1.

The movable weighted food barrier is shown with symbolic breaks in its length. The appearance of any portion of the article between the break lines forms no part of the claimed design.
